ROTARY PUMP FOR CORROSIVE LIQUID

Arthur O. Russell, White Plains, N. Y.

Application October 31, 1934, Serial No. 750,757

6 Claims. (Cl. 103—103)

The object of my invention has been to provide a rotary pump for corrosive liquids which can be made of glass or other non-corrosive material, and yet shall be so designed as not to permit the glass parts to touch each other when the pump is operating; and to such ends my invention consists in the rotary pump herein-after specified.

In the accompanying drawing:

0 Fig. 1 is a vertical cross section of a pump embodying my invention; and

Fig. 2 is a perspective view of the glass rotor.

The typical example of a pump embodying my invention, which is shown in the accompanying drawing, comprises a rotor 10 which is integral with or mounted upon a shaft 11 that is housed in a sleeve 12 of metal which is supported in a bearing block 13, said rotor and shaft being formed of glass, quartz or other non-corrosive material. Throughout the specification and claims the term "glass" is to be understood as including quartz or other amorphous or crystalline non-corrosive material.

The rotor is enclosed in a casing comprising a cap 14 and a back 16, which are formed of glass and which conform fairly closely to the rotor but do not touch the latter at any point during rotation, since to do so would soon destroy the pump.

0 In the present example, the hub 15 of the back 16 and the adjacent face of the bearing block 13 each has a conical recess therein that together form a recession, in which packing 17 is placed to prevent the escape of the corrosive liquid being pumped. The said cap and back of the casing are clamped together, as by bolts 18 that draw a metal ring 19 which bears on the periphery of the cap 14, and a similar ring 20 that bears on a flange 21 that is formed on or connected with the bearing 13. The cap 14 has an inlet 22, through which the liquid to be delivered enters the pump. The rotor 10 has a depression 23 opposite entrance 22, and from the said depression there radiate a series of gutters 24 which are at an oblique angle to the axis of the rotor, and which slant backward in the direction of the said entrance. The said gutters 24, in the present example, extend about one-half of the radial dimension of the chamber within the cap 14 and then merge into gutters 25 which extend at an angle to the axis of rotation, but in the opposite direction from the gutters 24.

The cap of the casing approximately fits the rotor, but sufficient clearance or space 26 is provided between the rotor and the cap so that they

cannot by any possibility strike or rub each other. This avoidance of contact between the rotor and the cap or the back 16 of the pump permits each of said parts to be made of glass, fused quartz, or other non-corrosive material. 5

The exit from the pump is an opening 27 in the back 16, which is located approximately at the same radial distance as the exits of the gutters 25.

In the operation of the aforesaid example of my pump, the rotor being in motion, the liquid in the gutters 24 is thrown outward by centrifugal force. The said pressure upon the liquid in the casing around the rotor, so that the sucking of air into or retention in the pump is prevented. The water tries to go straight out, perpendicularly to the axis of rotation; but the gutters are inclined diagonally across the path which it would follow, and this builds up a pressure in the columns of water in the gutters 24. The said pressure drives the columns of water in the said gutters 24 against the slanting inner surface of the cap 14, and causes them to rebound and enter the gutters 25 and the gutters 25 being inclined away from the axis in the direction of flow of the water, conduct the water under pressure to and through the outlet 27. Thus, the continuous and accumulated pressure from the gutters 24 provides a continuous column of water through the exit 27. Stated otherwise, the fluid starting from the point 28, flows outward through the gutters 24, which are formed in the outer face of the impeller, which is that of a re-entrant cone, the cross-sections of the said gutters preferably remaining the same throughout their length, thus controlling or synchronizing the speed and volume of travel in the said gutters. 30

At the outer or delivery end of the gutters 24, the path of the fluid changes and follows the gutters 25, which have the slant of the exterior of a cone and which conduct the fluid to the delivery orifice 27, the gutters 25 being preferably of the same cross-section throughout their length, so that the fluid travel is still controlled. The aforesaid construction of the two 45 sets of gutters, by controlling the flow of the fluid, eliminates the necessity of a seal or tight-fitting connection, because, at the point 26, which is the dead area, an anti-friction fluid seal for the impeller is formed and the fluid is expelled 50 through the outlet or delivery pipe 27, which, being in line with the exit of the gutters 25, the fluid is freely forced through the said outlet. This feature eliminates the necessity of having a bleeder device or passage in said casing where 55

the two halves of the casing 14 and 16 join. Owing to the fact that the internal area of casing 14 is continually increasing in the direction of flow of the fluid, and following the angles of the impeller 10, any air or gas which might be drawn in through the inlet 22 is expelled from the fluid at the ends of the gutters 24, owing to the hugging effect of the heavier element in its passage through the said gutters. The gases at this point are expelled into the space 26 and are carried with the fluid through the gutters 25 and space 26 to the delivery outlet 27. This feature enables this pump to handle fluids and gases, either combined or intermittently, without being coming air or gas-locked. The space 26a between the casing 16 and the impeller 10 is the equalizing and high-pressure space of this pump. In this space, a thrust is built up against the back of the impeller 10 by the reaction occurring in the gutters 24, which thrust is compensated by the positive pressure in the space 26a. Fluid, in its escape to packing 15, supplies or provides a fluid bearing to compensate for this thrust. Owing to the hugging effect of the fluid as described in gutters 24 and 25, the space 26, surrounding the impeller or rotor 10 on its face and periphery, becomes a dead area affording an anti-friction fluid seal or bearing to the impeller or rotor and obviating the necessity in a pump of this type for any seal or tight-fitting connection.

Thus is effected a centrifugal pump of novel design and principle, of great efficiency and positiveness of action, capable of delivery at considerable pressure and in great volume, capable of self-priming from dry from a substantial vertical depth of suction, and of a design the construction of which is such that considerable clearances in all directions, namely, space 26, can be permitted, indeed are necessary, between the impeller or rotor 10 and the casings 14 and 16. These clearances, combined with the facts (a) and (b) detailed below, enable this pump to be made wholly of glass, hard rubber, porcelain, stoneware, etc., as well as of acid-resistant metals and non-acid-resistant metals: (a) The impeller or rotor 10 runs entirely within a fluid seal or bearing formed by the fluid in spaces 26 and 26a. It is thus balanced, compensated and largely carried which obviates the necessity for any bearing whatever other than packing 17, which itself may be one of the well-known acid-resisting packings; and (b) the impeller or rotor 10 and the casings 14 and 16 are of an extremely simple, though of an entirely novel, design which can be pressed or moulded in glass or in any of the materials or metals enumerated above, *inter alia*. Nothing limits the size of a pump of this type except the ultimate centripetal strength of the particular material of which the impeller or rotor is made. Furthermore, the aforesaid novel design of the rotor and casing provide a self-priming pump of such efficiency that the rotor can be made considerably smaller than the casing and thus can be made of glass. The packing 17 prevents the entrance of air between the shaft 11 and the back 16, which would otherwise take place; it also, by engagement with the enlargement flange 29 on the glass shaft, serves to maintain the rotor in a position in which it does not touch either the cap or the back of the casing. Since neither the shaft, the cap nor the back touch each other, they can be made of glass without danger of breakage. Furthermore, the principle by which the liquid is packed into the spaces between the

said parts prevents the inefficiency which otherwise would be present, due to the sucking of air into the pump chamber.

The opening in the back 16, through which the shaft passes, is preferably made so that the said parts do not touch each other. The provision of the packing 17 between the conical wall of the back 16 and the opposite conical depression in the bearing 13 prevents the liquid or air from passing through the opening in the back and escaping, thus again avoiding the necessity of two glass parts touching each other.

The principles of my pump can be applied in many different ways, and my invention is not to be limited to the specific form chosen for illustration. Moreover, metal parts coated with a non-corrosive enamel could be used in place of the glass or quartz elements used in the illustrative example.

The principle of my pump by which the gutters not only extend radially but up-hill, so to speak, with a component of motion lengthwise of the axis of the shaft, and especially when a component is used first in the direction of the axis one way, and then with such a component in the opposite direction, tends to keep the liquid in the gutters so as powerfully to propel the liquid toward and through the exit.

When the claims state that the gutters make an acute angle with the axis, the said angle is to be measured clockwise from the gutters to the axis in Fig. 1.

I claim:

1. In a pump for delivering corrosive liquids, the combination of a glass rotor having gutters extending radially outward from a central inlet and having a component of motion lengthwise of the axis of rotation, said rotor also having gutters in its periphery, inclining from the discharge ends of said first-mentioned gutters radially outward and at an angle to the shaft in the opposite direction from said first-mentioned gutters.

2. In a pump for delivering corrosive liquids, the combination of a rotor in the shape of a frustum of a cone rotatable about the axis of the frustum and having gutters longitudinally of its slant surface, the top of the frustum having a depression in the form of an inverted conical frustum, the slant surface bounding the depression having radial gutters meeting the inlet ends of the first-named gutters, and a casing enclosing said rotor shaped approximately counterpart to but not touching said rotor, said casing having an inlet communicating with the axial central part of the rotor and having an outlet communicating with the radially outermost part of the rotor.

3. In a pump for delivering corrosive liquids, the combination of a rotor in the shape of a frustum of a cone rotatable about the axis of the frustum and having gutters longitudinally of its slant surface, the top of the frustum having a depression in the form of an inverted conical frustum, the slant surface bounding the depression having radial gutters meeting the inlet ends of the first-named gutters, said first-named gutters being more nearly parallel to the axis of rotation than the second-named gutters, and a casing enclosing said rotor having an inlet communicating with the axial central part of the rotor and having an outlet communicating with the radially outermost part of the rotor.

4. In a pump for delivering corrosive liquids, the combination of a glass rotor having a hollow

therein shaped like an inverted conical frustum with radial gutters formed in its inner slant surface, said rotor also having a positive frustum of a cone extending outwardly from the outer edge of said hollow, said positive frustum having gutters in its slant surface communicating with the gutters in the inverted frustum, and a casing enclosing said rotor, said first-mentioned gutters being more inclined to the axis of rotation than 5 said second mentioned gutters, all of said gutters being of uniform cross-section throughout, and said casing having an axial inlet and an outlet approximately opposite the delivery ends of said second-mentioned gutters.

10 5. In a pump for delivering corrosive liquids, the combination of a glass rotor having gutters extending radially outward and having a component of motion lengthwise of the axis of rotation, said rotor also having gutters in its periphery inclining from said first-mentioned gutters

radially outward and at an angle to the shaft in the opposite direction from said first-mentioned gutters, and a casing enclosing said rotor, said casing and rotor being substantially spaced apart, said casing having an inlet communicating with 5 the axial central part of the rotor and having an outlet communicating with the radially outermost part of the rotor.

15 6. In a pump for delivering corrosive liquids, the combination of a rotor having a hollow 10 therein that is shaped like an inverted conical frustum, and radial gutters in the slant surface of said hollow, a casing enclosing said rotor, said casing being spaced away from and yet substantially parallel to the hollow side of said rotor, the back of said rotor and the adjacent portion of the casing being plane surfaces not touching each other.
